UNITED STATES PATENT OFFICE.

SHERMAN S. LAWSON, OF CHICAGO, ILLINOIS.

FEED-WATER HEATER.

1,130,412.

Specification of Letters Patent.

Patented Mar. 2, 1915.

Application filed March 7, 1914. Serial No. 823,811.

To all whom it may concern:

Be it known that I, SHERMAN S. LAWSON, a citizen of the United States, and a resident of Chicago, in the county of Cook and State of Illinois, have invented certain new and useful Improvements in Feed-Water Heaters, of which the following is a specification.

My invention relates to feed water heaters, particularly to feed water heaters for locomotives.

Among the important objects of the invention are to provide feed water heater apparatus which can be readily applied to boilers without requiring reconstruction or re-arrangement in such boilers; to provide heating mechanism consisting in greater part of ordinary piping and fittings which can be readily inserted in one of the flues of a boiler, to arrange the heating mechanism in such manner that the pipes are readily accessible from the exterior of the boiler without the necessity of removing any boiler parts in order that fittings may be readily and quickly cleaned; to provide such construction and arrangement that a great part of the otherwise wasted heat in the smoke-box of a boiler will be utilized in heating the feed water; to provide valve mechanism for preventing draining of the heater pipes during service of the boiler whereby such pipes will be prevented from being burned out and will assist in heating the boiler water and generating steam; and in general to provide simple and efficient feed water attachment for boilers, particularly locomotive boilers.

In the accompanying drawings which clearly illustrate the features of the invention Figure 1 is a side elevation of a locomotive boiler showing the feed water attachment applied thereto, Fig. 2 is a front elevation of the boiler, Fig. 3 is an enlarged sectional view on plane 3—3, Fig. 2 and Fig. 4 is an enlarged sectional view of the front end of a modified arrangement.

Although my invention may be applied to different classes of boilers, the drawings show it applied to a locomotive boiler which has the fire-box 6 and smoke-box 7 of well known construction and arrangement, flues 8 extending from the fire-box tube sheet 9 to the smoke box tube sheet 10 to connect the fire-box with the smoke-box

from which the stack 11 extends. My improved water heating mechanism is in the nature of an attachment which can be inserted in one of the regular flues of the boiler or for which a special flue may be provided. Each heater mechanism is shown as comprising pipes 12 and 13 connected at their inner ends by a joint fitting 14 and terminating at their front ends in a header 15. The header is secured to the smoke box front 16 at the outside thereof and the pipes 15 will extend entirely across the smoke box and through the receiving flue to within a short distance of the fire box tube sheet. Referring particularly to Fig. 3, the header comprises two preferably cylindrical passageways or chambers 17 and 18 registering respectively with the pipes 12 and 13. These chambers communicate respectively with the inlet and outlet laterals 19 and 20, the inlet 19 being connected by piping 21 with the source of water supply, and the outlet 20 being connected by piping 22 with the boiler, a valve 23 being preferably interposed in this pipe at the boiler. Thus the feed water first passes into chamber 17, thence inwardly through pipe 12 and outwardly through pipe 13 to chamber 18, and from there to the boiler. In boilers the heat travels rapidly through the flues particularly when the exhaust steam is blown through the stack, the result being that the water about the flues will have time to absorb only the heat at the outer part of the flues, the heat passing through the more central parts of the flues being more or less wasted. However, by applying the feed water heater pipes in a flue, the heat and burning products flowing along the more central part of the flue will be absorbed by the feed water and the feed water will be rapidly heated without drawing any of the heat from the water in the boiler about the flue. In fact, the feed water heater pipes will act more or less to baffle and retard the flow of burning products through the flue in order that the water surrounding the flue will have time to absorb a greater number of heat units. A check valve 24 is preferably inserted in the supply pipe 21 close to the header. In service the valve 23 is always open, and when the water pump or injector stops supplying feed water the check valve 24 will close and will retain

water in the feed water heater pipes 12 and 13 which will then serve like ordinary water tubes to heat water and generate steam. By being thus always filled with water there will be no danger of the pipes burning out.

As before stated, the header is secured to the outside of the smoke box front. As shown the header has a flange 25 by means of which and bolts 26 it may readily be secured in place over the opening 27 provided in the smoke box front. The pipes 12 and 13 may be secured directly to the header but preferably they are detachably secured by couplings 28 to nipples 29 extending from the header. In the outer wall of the header and in alignment with the pipes 12 and 13 are threaded openings 30 for receiving detachable plugs 31. When it is desired to clean the pipes the plugs are removed and a suitable tool inserted through the plug opening, the corresponding chamber and the pipe extending therefrom, such cleaning being thus accomplished entirely from the exterior of the boiler and smoke-box without need of removing any of the smoke-box parts. Furthermore, the pipes extend through the full length of the smoke box and the feed water is thus able to absorb a great quantity of heat units which would otherwise pass out of the stack and be wasted.

In Fig. 4 I have shown an arrangement in which the heating surface is increased in the smoke box. An extended header 32 is shown having the inlet chamber 17 at its one end and the outlet chamber 18 at its opposite end connected respectively with the water supply and the boiler as in the arrangement of Fig. 3. However, a plurality of heater loops 33 are interposed between the main loop 12, 13 and the outlet pipe 22. Each of the loops 33 comprises two parallel pipes 33^a and 33^b extending across the smoke stack and connected by a joint 33^c, the front ends being connected with the header in the same manner as are the main pipes 12 and 13, the pipes of the loop connecting with the header at opposite sides of a partition 32'. The water enters the header and then circulates through the pipes 12 and 13, and then serially through the auxiliary loops as indicated by arrows to be finally delivered to the boiler. With such auxiliary arrangement practically all the available heat in the smoke box may be utilized for heating the water. Opposite each of the loop pipes the header has an opening 34 receiving the plug 35, the arrangement being precisely as in the main pipes 12 and 13 in order that the auxiliary loop pipes may be made readily accessible and cleaned. Furthermore, by merely removing the bolts 26 an entire heater unit can be quickly withdrawn. This is very important as a new unit can be quickly substituted for one which has be-

come defective without loss of time and without in any wise disturbing the normal operation of the boiler.

One or more feed water heater units may be applied. As shown in Fig. 2 two such heater units are applied at opposite sides of the boiler. Also, instead of having only two pipes in the main loop a greater number could be used, two, however, being preferable. Other changes and modifications may also be made and I do not therefore desire to be limited to the precise construction and arrangement shown and described.

I claim as follows:

1. In combination with the fire box, smoke box and the flues of a boiler, of a feed water heater unit comprising a header adapted to be secured on the outside of the smoke box front, said smoke box front having an opening therethrough, piping extending from said header into the smoke box and into and through one of the boiler flues, said header having an inlet and an outlet for water, the water flowing through said piping to be heated by the products of combustion passing through said flue and said smoke box.

2. In combination with a water heating structure involving a fire box, a smoke box having an opening to the exterior, and a boiler having flues extending between the fire box and the smoke box, of a feed water heater unit comprising a header adapted to be secured on the outside of the smoke box, and a piping loop communicating with and extending from said header across said smoke box and into a flue of said boiler, said header having inlet and outlet for water.

3. In combination with a water heating structure involving a fire box, a smoke box having an opening to the exterior, and a boiler having flues extending between the fire box and the smoke box, of a feed water heater unit comprising a header adapted to be secured on the outside of the smoke box, a main piping loop communicating with and extending from said header across the smoke box and into a flue of said boiler, a plurality of auxiliary loops communicating with and extending from said header through said opening and into the smoke box, said header having a feed water inlet and having an outlet connected with said boiler.

4. In combination with a fire box, smoke box and the flue of a boiler extending therebetween, the smoke box front having an opening opposite the flue, of a feed water heater unit comprising a header adapted to be detachably secured on the outside of the smoke box front about said opening, a piping loop communicating with and extending from said header across the smoke box into said flue, a feed water inlet for the header and a controllable water connection from said header to the boiler.

5. In combination with a fire box, smoke box and the flue of a boiler connecting between the fire box tube sheet and the smoke box tube sheet, the smoke box front having an opening opposite said flue, a header adapted to be detachably secured to the outside of the smoke box front about said opening, parallel pipes extending from said header across the smoke box and into said flue and joined at their inner ends, an inlet chamber and an outlet chamber in said header, said chambers communicating respectively with said pipes and connected respectively with a source of water supply and with the boiler, and a plugged entrance to each chamber in alinement with the pipe extending therefrom whereby said pipes may be readily cleaned.
6. In combination with a fire box, smoke box and the flue of a boiler connecting between the fire box tube sheet and the smoke box tube sheet, the smoke box front having an opening opposite said flue, a header secured to the smoke box at said opening, a main piping loop extending from said header across the smoke box and into said flue, a plurality of auxiliary piping loops extending from said header into the smoke box, inlet and outlet for said header adapted for connection respectively with feed water supply and the boiler, and partitions and passageways in said header for causing serial flow of the water through the loops.
7. In combination with a fire box, smoke box and the flue of a boiler connecting between the fire box tube sheet and the smoke box tube sheet, the smoke box front having an opening opposite said flue, a header se-
- cured to the smoke box at said opening, a main piping loop extending from said header across the smoke box and into said flue, a plurality of auxiliary piping loops extending from said header into the smoke box, inlet and cutlet for said header adapted for connection respectively with feed water supply and the boiler, and partitions and passageways in said header for causing serial flow of the water through the loops, said header and loops forming a unitary structure adapted to be bodily removed from the smoke box.
8. In combination with a fire box, smoke box and the flue of a boiler connecting between the fire box tube sheet and the smoke box tube sheet, the smoke box front having an opening opposite said flue, a header secured to the smoke box at said opening, a main piping loop extending from said header across the smoke box and into said flue, a plurality of auxiliary piping loops extending from said header into the smoke box, inlet and outlet for said header adapted for connection respectively with feed water supply and the boiler, partitions and passageways in said header for causing serial flow of the water through the loops, said header having a cleaning opening in alinement with each of the loop legs, and a plug for each cleaning opening.

In witness whereof, I hereunto subscribe my name this 4th day of March, A. D., 1914.

SHERMAN S. LAWSON.
